FIG. 1

FIG. 2

FIGURE 1 is a front elevational view of a combined water control and escutcheon for a bathtub or the like showing my new design; FIGURE 2 is a side elevational view thereof, a portion of the escutcheon being broken away for convenience of illustration.

The dominant features of my design reside in the portions shown in full line.

I claim:

The ornamental design for a combined water control handle and escutcheon for a bathtub or the like, substantially as shown and described.
